(57) **CLAIM**

The ornamental design for a fruit juice extractor, as shown and described.

DESCRIPTION

FIG. 1 is a front perspective view of a fruit juice extractor, showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines shown in FIGS. 1-6 depict other components of the fruit juice extractor and are included for environmental purposes only.
